UNITED STATES PATENT OFFICE.

GEORGE INNES, OF DAVENPORT, IOWA.

GRAIN SHOCKER.

Application filed December 28, 1922. Serial No. 609,421.

My invention relates to certain improvements in a machine for shocking grain, such as illustrated in my prior United States Letters Patent No. 1,512,769, dated October 21, 5 1924.

Bundles of grain, as they are delivered from the binder deck of a harvester binder, do not, as is generally supposed, assume a truly circular form in cross section; but instead, assume an elliptical form and are delivered along and from the binder deck with the longitudinal dimidiate plane of the major axis thereof, parallel to the plane of the binder deck.

15 In order to form a shock which will reasonably withstand the force of the elements, it is essential that the individual bundles composing the shock be set at an acute angle to the vertical centre of the shock with the aforesaid major axes of the elliptically formed bundles lying in a line parallel to the longitudinal centre line of the base of the shock. To accomplish this result, the said major axis of each bundle must be maintained in a certain definite position from the time the bundle leaves the deck of the binder until it is placed in its correct position in 20 the shock forming basket.

One object of my invention is to provide 30 mechanism whereby bundles of grain may be received successively from the binder deck, the aforesaid major axis of each elliptical bundle being definitely maintained while the bundle is being positioned on the table of 35 the shocker and while a second bundle is likewise positioned on the table in proper angularly opposed relationship to the first bundle, and the two so positioned bundles gripped and maintained in their proper relation one with the other, by a grapple, which positively places the aforesaid pair of 40 bundles in the basket of the shocker in the correct relationship for forming a shock of the character described above.

45 In the accompanying drawings:

Fig. 1 is a rear elevation of a machine for shocking grain, illustrating my improved means for transferring and locating the bundles of grain, the parts being in the first 50 receiving position;

Fig. 2 is an enlarged view of a portion of Fig. 1, showing the parts in the bundle-holding position;

Fig. 3 is a plan view of the mechanism shown in Fig. 2;

55

Fig. 4 is an enlarged plan view of the clutch operating mechanism;

Fig. 5 is a sectional view on the line 5—5, Fig. 4;

Fig. 6 is a diagram of the operating cams 60 and the levers actuated by the cams;

Fig. 7 is a rear elevation illustrating a modification of the invention;

Fig. 8 is a plan view of the mechanism shown in Fig. 7 and

65

Figs. 9 and 10 are detail views of certain of the parts shown in Figs. 7 and 8.

In the type of grain shocker to which my invention relates, the shocking device A is secured to an ordinary harvester binder B. 70 It contains three distinct parts, namely, the means C for receiving the bundles of grain from the deck b of the binder and locating the bundles in pairs; a grapple D for transferring the pair of bundles from the locating means and carrying the pair of bundles to the shock-forming basket; and the shock-forming basket E, in which the bundles are arranged properly and which discharges the bundles from the machine onto the ground. 75 80

Referring to Figs. 1, 2 and 3, 1 is the main frame of the machine A for shocking grain, which is attached to the binder B, as illustrated in the application hereinbefore referred to. 2 is the main shaft of the shocker having a traction wheel 3 at each end, as shown in Fig. 1.

4 designates the guide bars over which the bundles of grain are carried, forming a slatted table 5, as clearly shown in Fig. 3. 90 The bars are secured rigidly to the main frame 1. Secured to the table 5 are three fixed fingers 6 against which the first bundles rest.

7 designates the receiving tongs. There 95 are two pairs of tongs in the present instance. The tongs positively grip the bundle of grain and transfer it in position to be located properly. As the tongs grip the bundle, they tear it away from another bundle being formed on the table b, insuring delivery of the bundles from the binder and not depending upon the mechanism of the binder to feed each bundle to the shocking mechanism.

100

105

Each pair of tongs consists of a long arm

8 having a curved extension 9 and a short, curved arm 10 pivoted to the long arm at 11. The long arm of each pair of tongs is pivoted at 12 to a bearing 13 on the main frame. On the same pivot 12 is a bell crank lever 14. The long arm 15 of this lever is connected by a link 16 to the short, curved arm 10 of the tongs and the short arm 17 of the bell crank lever is connected to a long link 18, which, in turn, is connected to a crank 19 on a short shaft 20 mounted in bearings 21 on the main frame of the machine. The shaft 20 has a crank 19 at each end, one crank operating one pair of tongs 15 and the other crank operating the other pair of tongs. On the shaft 20 is a spiral gear 22, which meshes with a spiral pinion 23 loosely mounted on the main shaft 2. On the hub of this pinion are clutch teeth 24, which are in position to be engaged by the teeth of the clutch sleeve 25, which is splined to the shaft 2 so that it can slide on the shaft, but must turn therewith. Back of the sleeve is a spring 26, which rests against a collar 27 secured to the shaft. This spring tends to force the clutch in engagement with the teeth 24 of the pinion. The clutch is held out of engagement by a yoke 28, which extends into a groove in the sleeve 25. The yoke is secured to a short shaft 29 and has an arm 30 on which is a sliding block 31 to which is secured a rod 32. The rod extends through a bearing 33 on the yoke. Between the bearing and the block 31 is a coiled spring 34. The block has a projection 35, which limits its outward movement, Fig. 5.

The rod has a lateral projection 36, which is engaged by a trigger 37 pivoted at 38 to a lever 39, pivoted at 40 on the main frame 40 of the machine. As shown in Fig. 1 the deck *b* of the binder *B* is provided with bundle forming and tying mechanism *B*¹, forming no part of the present invention, which is operated by a shaft *b*¹ to which is secured a lever 40^a connected by a link 40^b to one end of a lever 40^c pivoted to the frame 1 of the shocker *A*. The opposite end of the lever 40^c is connected by a link 40^d to an arm 40^e secured to the lower end of the pivot shaft 40 of the lever 39, whereby, the lever 39 is actuated by the tying mechanism on the binder. A spring 41 tends to hold the trigger in its extended position, but allows the trigger to turn on its pivot on returning when it passes the projection on the rod 32.

On the face of the spiral gear 22 is a pin 42, which comes in contact with the block 31, as shown in Fig. 5, after each bundle is carried into position. As the pin moves forward, it turns the yoke 28 on its pivot, which withdraws the clutch sleeve 25, stopping the movement of the shaft 20, the tongs being in position of rest to receive another bundle, as shown in Fig. 1.

When the block 31 is withdrawn from the path of the pin 42 by the tying mechanism of the binder, the clutch sleeve 25 is moved into engagement with the teeth 24 on the hub of the pinion 23 by the spring 26, and the shaft 20 is turned until the pin 42 comes in contact with the block. 70

On the shaft 29 is a hooked latch 43, which engages a pin 44 on the spiral gear wheel 22 and prevents back lash when the clutch is thrown out. The latch has a heel 45, which is in the path of the projection on the yoke 28 so that, when the yoke is moved by the spring 26, it will move the latch clear of the path of the pin 44. 75

As this machine is designed to place two bundles in position to be engaged by the grapple, and, as the binder delivers one bundle at a time, means must be provided to assemble the bundles side by side. This is 80 accomplished, as follows:

Pivoted to the main frame, at 46 and at 47, are arms 48 and 49, respectively. These arms are straight and extend above the slatted table, when elevated. When turning 90 on their pivots, they are located below the table and under the tongs.

As the first bundle is raised onto the slatted table by the tongs, the arms 48 and 49 follow up and engage the bundle, moving 95 it out of the tongs, which have opened on their return movement. The arms move the bundle over the table to its final position against the stationary fingers 6. As the bundle is moved onto the table, it comes in contact with spring-pressed arms 50 and 51, which are pivoted at 52 and 53, respectively, and extend through slots in the frame formed by plates 54. The springs 55 are attached to the arms and to pins on the main frame. These spring-pressed arms 100 yieldingly hold the bundle against the arms 48 and 49 and prevent the bundle moving out of position.

The arms 48 and 49 are controlled by cams 110 on a cam shaft 56, journaled in a pair of brackets 57, extending from the main frame of the machine. On the shaft 20 is a gear wheel 58, which meshes with a wheel 59 on the shaft 56. The gears are proportioned 115 two to one. The arm 48 is a center arm and is located between the head of the two bundles *x*-*x*, Figs. 2 and 3. The arm 48 has a short extension 60 connected by a link 61 to a lever 62 pivoted at 63 to one of the brackets 57. On the lever is a roller 64, which rests against the face of a cam 65 on the shaft 56. The cam is so cut as to give the arm 48 the proper movement in time with the other mechanism. 120

The arm 49, which rests against the butt of the first bundle, is controlled by a cam 66 on the shaft 56 through a lever 67, pivoted at 68, and having a roller 69, shown by dotted lines in Fig. 6. The lever 67 is con- 125

nected to the arms 49 by a link 70. When the arms 48 and 49 are raised, as in Fig. 2, they hold the first bundle firmly against the fingers 6.

5 An arm 71, pivoted to the main frame at 72, moves with the arms 48 and 49 and acts, with the arm 48, as a stop and holder for the second bundle, spacing the butts of the bundles. The arm 71 is connected by a link 10 73 to a lever 74 pivoted at 68 and having a roller 75, which rests against a cam 76 on the shaft 56.

Pivoted to the table 5, at 77 and at 78, are curved fingers 79 and 80, respectively. 15 These fingers are located below the table, as in Fig. 1, when the bundles are being placed in position. When the second bundle is being located in position on the table by the tongs, the fingers 79 and 80 are raised into 20 the position shown in Fig. 2, holding the second bundle against the arms 48 and 71, and allowing the tongs to return to their position of rest, as shown in Fig. 2. The finger 79 is connected to a lever 81 by a link 82. 25 On the lever is a roller 83 resting against a cam 84.

The finger 80 is connected to a lever 85 by a link 86. On the lever is a roller 87 resting against a cam 88. The several cams 30 on the cam shaft 56 are so timed that each arm will have a movement at the proper time, and, when the arms are all in the raised position, they remain in that position for a given length of time to allow the 35 grapple to engage the bundles and remove them from the table.

Attached to the binder deck *b* is a series of slats 99, bent at their outer ends and attached to a cross bar 100, Fig. 1. The slats 40 and bar form a continuation of the deck *b*. The bar is so located in respect to the tongs that the extensions 9 of the tongs 7 rest on the bar so that a bundle, when released by the binding mechanism, passes directly into 45 the tongs without changing its position. The tongs positively engage the bundles and move them into position to be grappled by the grapple D.

The tongs receive and grasp one bundle 50 while another bundle is held in the binder as it is being tied. The tongs, as they move away from the deck, pull one bundle from the other so that each bundle is a separate unit. This is especially important when 55 tangled grain is handled.

It will be understood that the bundles, when formed and tied, are oval. The longest axis lies parallel with the surface of the deck, consequently, when the bundle reaches 60 the tongs, it is still in the same position. When the tongs carry the bundle to a position on the table, the bundle is arranged on edge, the broad side of each bundle being face to face. This is important, as the 65 bundles must be arranged with their broad

sides face to face in the shock to make a perfect shock. By assembling the bundles in this manner on the table, they will remain in this position while passing through the machine, as both bundles are controlled positively after they leave the table. 70

The grapple D, Fig. 1, has fingers *d*, *d'*, which are operated by mechanism timed with the boom *d*, and the means for turning the grapple so that, when the boom is lowered to the table, they positively engage the two bundles held by the arms and remove them from the table without changing their relative positions. The grapple is then turned so as to turn the bundles in position 80 with their butts to the rear, all as clearly set forth in the above mentioned patent. They are then deposited in the basket E in the same relative position in which they were held by the arms. 85

When the basket has been loaded with a predetermined number of bundles, it is turned, and its load deposited on the ground to form a shock.

By the above construction, it will be seen 90 that the bundles of grain are engaged positively by the mechanism as soon as they are released by the binder and that they are held firmly in their several positions by the mechanism until they are deposited on the 95 ground in the form of a shock.

In Figs. 7 and 8, a modification is illustrated, in which a dividing board is substituted for the two arms 49 and 71. 89 designates the dividing board mounted on a 100 stud 90 on the main frame 1 and actuated by a cam 91 through a lever 92 and link 93. The arm 48^a is actuated by a cam 65^a and link 61^a. The cams 91 and 65^a are on the cam shaft 56^a. 105

In Fig. 8, a modification of the means for actuating the clutch sleeve 25^a is shown. On the yoke lever 30^a is pivoted a dog 31^a, which in turn carries a pawl 98 pivoted thereto and projecting into the path of 110 movement of a head 94 on a rod 95 connected to an arm 96 of a lever 97 pivoted to the frame. The lever 97 is connected to the tying mechanism of the binder. The head 94 of the rod moves past the projecting end 115 of the pawl, and, on its return movement, engages said pawl 98 and swings the dog 31^a laterally from under the clutch withdrawing pin 42^a, thereby releasing the yoke 30^a and permitting the clutch sleeve 25^a to 120 engage the teeth 24^a of the pinion 23^a. When the rod 95 is fully retracted, the dog is released and returns into position to be engaged by the pin 42^a carried by the gear 22^a. 125

I claim:

1. In a grain shucker, adapted to receive bundles of grain directly from the binder deck of a harvesting machine whereon each bundle assumes an elliptical form in cross- 130

section, with the major axis of said ellipse parallel to said binder deck, the combination of means for assembling said bundles in the form of a shock with the said major axes contiguously aligned longitudinally of said shock; and tongs adapted to occupy a position in direct and contiguous alignment with said binder deck and adapted to engage said bundles positively as they are delivered from said deck and to transfer them to be assembled in the form of a shock and to maintain said bundles with the major axes thereof, in a definite position.

2. In a grain shucker, the combination of tongs contiguously aligned with, and adapted to receive bundles of grain directly from, the binder deck of a harvesting machine and to transfer them positively into and subsequently release them in a given position at an intermediate station; means for maintaining said bundles in said given position in said intermediate station prior and subsequent to said release; a basket; and a grapple adapted to engage said bundles while in the control of said maintaining means and to transfer them to said basket.

3. In a grain shucker, the combination of tongs adapted to receive bundles of grain directly from the binder deck of a harvesting machine; means for operating said tongs to grasp said bundles of grain and arrange them in pairs; a basket; and a grapple for positively gripping the assembled bundles of grain and transferring them to the basket.

4. In a grain shucker, the combination of tongs, located at the delivery end of the binder deck of a harvesting machine and adapted to grasp the bundles as they are delivered from said deck and positively remove said bundles therefrom; a table, on which said bundles of grain are arranged in pairs, by the tongs; means for separating the butt ends of said pair of bundles and causing their head ends to engage and interlock with each other, in such a manner that the bundles are positioned at an angle relative to each other; a grapple adapted to engage said pair of bundles without disturbing their relation to each other; and a basket adapted to receive said pair of bundles from said grapple and maintain them in the same relative position in which they were assembled on the table.

5. In a grain shucker, adapted to receive bundles of grain directly from the binder deck of a harvesting machine whereon each bundle assumes a flattened form in cross-section; tongs adapted to successively remove said bundles of grain from said deck with the flat sides of said bundles engaged by the arms of said tongs; means for moving the tongs so as to bring each pair of bundles on edge with their flat sides opposite each other, their heads being in contact and

their butts separated at a definite angle; a basket; and a grapple adapted to engage the bundles and transfer them to the basket in the same relation in which they were assembled by the tongs.

6. In a grain shucker, adapted to receive bundles of grain directly from the binder deck of a harvesting machine, the combination of a table, fixed fingers projecting from said table; movable fingers on said table; tongs adapted to carry the said bundles of grain from said binder deck to said table.

7. In a grain shucker, adapted to receive bundles of grain directly from the binder deck of a harvesting machine, the combination of means for assembling bundles of grain in pairs; and tongs for carrying the bundles of grain from said binder deck to the assembling means.

8. In a grain shucker, adapted to receive bundles of grain directly from the binder deck of a harvesting machine, the combination of tongs, located in line with said deck when they are open; a slatted extension attached to said deck and in line therewith and with said open tongs and adapted to close the gap therebetween, in order that the said bundles will pass flatwise onto the lower arms of the tongs, from the deck; and means for operating said tongs in a manner to bring a pair of bundles into a position to be transferred to a shock forming basket.

9. In a grain shucker, adapted to receive bundles of grain directly from the binder deck of a harvesting machine, the combination of a table; a grapple; tongs; means for operating the tongs to carry the bundles from the binder deck to the table; arms; and means for actuating said arms to move the bundles over the table in position to be engaged by the grapple.

10. In a grain shucker, adapted to receive bundles of grain directly from the binder deck of a harvesting machine, the combination of a table; a grapple; tongs arranged to receive the bundles from the deck, one at a time; means for actuating the tongs; two sets of arms; and means for operating said arms, whereby one bundle is located in position for the grapple by one set of arms, and another bundle is placed at the side of the first mentioned bundle by the other set of arms.

11. In a grain shucker, adapted to receive bundles of grain directly from the binder deck of a harvesting machine, the combination of two sets of tongs, one set arranged to engage the head ends of the bundles and the other set arranged to engage the butt ends thereof, as the bundles pass from the deck; a table; means for moving the tongs to place the bundles on the table; arms adjacent the table for gripping the head and butt ends of the bundles and for carry-

ing the bundles over the table; a basket; and a grapple for transferring the bundles from the table to the basket.

12. In a grain shocker, adapted to receive 5 bundles of grain directly from the binder deck of a harvesting machine, the combination of a frame attached to the harvesting machine; a slatted table attached to said frame; fixed fingers attached to said table; 10 movable spring-controlled fingers, pivoted to the frame and projecting above the table; tongs for receiving the bundles of grain and delivering them, one at a time, onto the table and against the spring-controlled fingers; a 15 crank shaft for operating the tongs; arms pivoted to the frame and normally lying below the table; cams for turning the arms on their pivots; means for rotating the cams so as to move the arms against the side of the 20 bundles opposite the spring controlled fingers and to move the bundles into position against the fixed fingers; means for releasing the tongs from the first bundle and returning them to receive another bundle of grain 25 from the deck; curved arms; cams for raising said arms to engage the side of the second bundle, opposite the first projected arms; a shock forming basket; and a grapple for transferring the assembled pair of 30 bundles to the basket.

13. In a grain shocker, adapted to receive bundles of grain directly from the binder deck of a harvesting machine, the combination of a frame attached to said harvesting machine and having a slatted table; a main 35 power shaft mounted in bearings on the frame; a crank shaft driven from said main shaft; a cam shaft driven from said crank shaft; tongs operated by said crank shaft; movable arms and fingers; cams on the cam 40 shaft operating the fingers in time with the tongs, in order to locate bundles of grain on the table as they are received from the deck of the harvesting machine; a shock forming 45 basket; and a grapple for transferring the bundles of grain from the table to the basket.

14. In a grain shocker, adapted to receive bundles of grain directly from the binder deck of a harvesting machine, the combination of a shocker frame; means on said frame 50 for assembling bundles of grain in pairs; a basket; a grapple; an extension on said binder deck; tongs, so located that their lower members form a continuation of said deck extension and having their outer ends 55 resting on said extension, allowing the bundles of grain to pass onto said tongs; means for actuating the tongs to transfer the bundles to the assembling means.

GEORGE INNES.
